(57) CLAIM

The ornamental design for a bag, as shown and described.

DESCRIPTION

1. Bag

1.1 : Perspective

1.2 : Front

1.3 : Back

1.4 : Right

1.5 : Left

1.6 : Top

1.7 : Bottom

The bag comprises a body which, when viewed from the front, has a substantially trapezoidal shape, with a bottom whose ends have a rounded contour and are curved upwards, so that said bottom resembles the board of a skateboard. The top of the body has a zipper that also extends down the sides of the body; in the reproductions of the design, the blurred elements in light gray (handles and shoulder strap) are not claimed.
